UNITED STATES PATENT OFFICE.

BENJAMIN FRANKLIN DAVIS, OF TRUEHEART, TEXAS.

RAIL-JOINT.

SPECIFICATION forming part of Letters Patent No. 406,033, dated July 2, 1889.

Application filed March 8, 1889. Serial No. 302,467. (No model.)

To all whom it may concern:

Be it known that I, BENJAMIN FRANKLIN DAVIS, a citizen of Trueheart, in the county of Ward and State of Texas, have invented 5 certain new and useful Improvements in Rail-Joints; and I do hereby declare the following to be a full, clear, and exact description of the invention, such as will enable others skilled in the art to which it appertains to 10 make and use the same.

My invention relates to an improvement in fish-plates or rail-joints for connecting the abutting ends of sections of railway-rails, its object being to provide strong and simple 15 means for connecting the adjacent ends of railway-rails and making the connection as nearly as possible as strong as any part of the rail.

A further object is to provide a rail-joint 20 made in a single piece of metal and which may be secured to the rail as well as to the ties upon which the rail rests.

A further object is to construct the rail-joint or fish-plate in such a manner that it 25 may be driven past a rail-joint to enable one section of the rail to be removed when desired.

With these objects in view my invention 30 consists in certain novel features of construction and peculiar combinations and arrangements of parts, as hereinafter set forth, and pointed out in the claims.

In the accompanying drawings, Figure 1 is 35 a perspective view of the device with one section of a railroad-rail in position. Fig. 2 is a plan view of the device. Fig. 3 is a section on the line $\alpha\alpha$ of Fig. 2.

A represents the base of the fish-plate 40 upon which the rail-sections B B rest. Projecting upwardly and inwardly from the base-plate A and in conformity with the flanges a of the rails are two integral plates C C'. The plates C C' terminate at their tops in vertical flanges b b' , which are a distance apart 45 sufficient to accommodate the web c of the rails B.

At one side of the fish-plate perforations d are made for the reception of spikes, said perforations passing through the plate C and 50 base A and being in alignment with notches d' made in the flange of the rail B. The

notches d' in the rail-flange will be made of greater width than the perforations d , in order to allow for expansion and contraction of the rails, said notches d' being preferably made 55 in both flanges of the rail to adapt either for the spikes.

At the meeting point of the diagonal plate C' and base-plate A notches e are made for the accommodation of spikes. These notches 60 are not made sufficiently deep to permit the spikes passing through them coming in conflict with the rail-flange.

At each end of the plate C' a thickened portion or rib f is formed extending upwardly 65 to the top of flange a and projecting at the lower ends beyond the longitudinal edge of the plate A to produce lugs g . These lugs are perforated for the reception of spikes, by means of which the fish-plate is held down at 70 its ends. It will be seen that the integral lugs or projections g broaden the bearing of the fish-plate on the ties, and that the spikes being passed through such broadened portions effectually prevent the ends of the plate 75 from rising from any cause. The fish-plate is further strengthened by a rib h , located midway between the ribs f and extending from the top of flange b' to the base of plate C'. The ends of ribs f are made parallel with 80 the ends of the fish-plate and produce broad surfaces. When it is desired to remove a section of the track, it is simply necessary to remove the spikes and strike against one of the broadened surfaces i of ribs f with a hammer or similar tool until the end of the fish-plate shall have passed the joint on the two rail-sections.

The fish-plate or rail-joint above described is simple in construction, being made of a 85 single piece of metal, and is effective in operation.

Having fully described my invention, what I 90 claim as new, and desire to secure by Letters Patent, is—

1. A fish-plate composed of a single piece 95 of metal adapted to embrace the flange and web of the rail, having perforations in one side to align with notches in the rail-flange and notches on the other side out of line with the rail-flange, ribs on one side of said fish-plate, and perforated lugs extending from

said ribs for the reception of spikes, substantially as set forth.

2. The combination, with a railroad - rail having notches in its flanges, of a fish-plate 5 composed of a single piece of metal adapted to embrace the flange and web of the rail, said fish-plate being plain on one side and provided on the other side with ribs, perforated lugs projecting from the ribs at the ends 10 of the fish-plate, said fish-plate being provided with perforations on one side to align

with notches in the rail-flange, and notches in the other side out of alignment with the rail-flange, substantially as set forth.

In testimony whereof I have signed this 15 specification in the presence of two subscribing witnesses.

BENJAMIN FRANKLIN DAVIS.
